UNITED STATES PATENT OFFICE.

WILLIAM H. CAMPBELL AND JESSE J. WILLINGHAM, OF PUEBLO, COLORADO.

DESIGN FOR A MEMORIAL TABLET.

SPECIFICATION forming part of Design No. 22,611, dated July 11, 1893.

Application filed May 12, 1893. Serial No. 474,027. Term of patent 7 years.

To all whom it may concern:

Be it known that we, WILLIAM H. CAMPBELL and JESSE J. WILLINGHAM, copartners as CAMPBELL & WILLINGHAM, citizens of the 5 United States, residing at Pueblo, in the county of Pueblo and State of Colorado, have invented and produced a new and original Design for a Memorial Tablet; and we do declare the following to be a full, clear, and exact description of the same, reference being had to the accompanying drawing, forming a part thereof.

Our design is a memorial tablet intended to represent the emblems of Purity, Hope and 15 Faith.

The drawing is a front elevation of the tablet.

A represents an ornamental wreath around the edge of the tablet, B a baseblock with an 20 opening in the side for an inscription and C a stone with a vase D on each side thereof.

These vases D have an anchor in front and are surrounded by an oval band to represent Hope. In the vases are white flowers which meet at top in the form of an arch, to represent 25 Purity. Within the arch is a young woman in a flowing white robe, with disheveled hair, and clinging with uplifted hands to the Rock of Ages, to represent undying Faith. Beneath the woman, we arrange a 30 bow and, above the arch of flowers, a dove on the wing and with a streamer in its bill.

What we claim is—

The design for a tablet herein shown and described.

In testimony whereof we affix our signatures in presence of two witnesses.

WILLIAM H. CAMPBELL.
JESSE J. WILLINGHAM.
